UNITED STATES PATENT OFFICE.

CHARLES F. WINCH, OF NEW YORK, N. Y.

MANUFACTURE OF HYDROCARBON LIQUIDS FOR USE IN INTERNAL-COMBUSTION ENGINES.

1,304,433.

Specification of Letters Patent. Patented May 20, 1919.

Application filed March 7, 1917. Serial No. 152,966.

To all whom it may concern:

Be it known that I, CHARLES F. WINCH, a citizen of the United States, and a resident of New York, in the county of New York 5 and State of New York, have invented certain new and useful Improvements in the Manufacture of Hydrocarbon Liquids Suitable for Use in Internal-Combustion Engines, of which the following is a specification.

The object of my invention is to obtain hydrocarbon liquid suitable, like gasoline, for use in an internal combustion engine.

The special object of my invention is to 15 produce a liquid of the character described in an economical manner.

In carrying out my invention I heat coal or its equivalent sufficiently only to drive off the more volatile gases or vapors which 20 are the smoke producing elements of the coal and expose petroleum to contact with the said volatile gases or vapors thus released to produce the said hydrocarbon liquid, all as hereinafter more particularly described. 25 By thus heating the coal only to the extent required to release such smoke producing elements which, as is well known, are the more volatile products or gases, I leave the coal nearly as valuable for fuel and coking 30 purposes as it was in its original condition and in some respects render it superior. It may be then burned or coked without the production of large volumes of smoke.

One way of carrying out my invention is 35 to inclose the coal in a suitable container or retort and apply heat to the same to cause the more highly volatile gases or vapors to pass therefrom. Said gases or vapors are brought into contact with the petroleum in any suitable way, as for instance by causing them to percolate through a body of petroleum in a suitable container, or the petroleum may be sprayed into a container together with the gas or 40 vapor from the coal. If desired the process may be carried on by the use of an agitator agitating the body of petroleum during the combining process.

Preferably the petroleum is kept at a comparatively low temperature during the process of combination. The result of the operation is that more or less of the more volatile gases or vapors derived from the coal are absorbed by the petroleum, thereby 45 converting the same into a hydrocarbon liq-

uid suitable for use like gasoline in an internal combustion engine, while at the same time leaving the coal with the major portion of its heat producing units so that, as above stated, the coal can be used for fuel or other purposes afterward with only a slight loss of value and, in the case of bituminous coal, will be free from the more volatile gases or vapors which are the smoke producing elements and ordinarily render bituminous coal 60 unsuitable for use in cities. 65

The stage of heating at which the coal ceases to give off the volatile gases or vapors suitable for use according to my invention cannot be exactly stated as it will vary with different grades or kinds of coal and would have to be ascertained by experiment in each particular case.

Ordinary bituminous coal may be employed although in general I contemplate 75 the heating of any carbonized product of the vegetable kingdom. It would be possible even to employ the partially carbonized material known as peat, when it is of such character as to readily give off hydrocarbon 80 gases.

My invention is not confined to any particular method of applying heat to the coal or other carbonized material to cause it to give off the said more volatile vapor or gases and my invention would include the use of internal combustion, steam or other hot vapor applied internally or externally. 85

In the accompanying drawings I have shown in diagram or skeleton apparatus 90 typifying apparatus suitable for use in carrying out my invention.

1 indicates the retort or heater in which the coal or other carbonized product of the vegetable kingdom is heated to the desired extent to drive off only the more volatile gases or vapors therefrom. 2 indicates a container for the hydrocarbon liquid like petroleum, naphtha or kerosene and 3 typifies any suitable purifier through which the 95 gas from 1 passes to remove impurities. 4 indicates the pipe which introduces the gas into the container 2, said gas being forced through the body of contained liquid or distributed through the same by the use of any mechanical pressure applying devices desired. 100

Likewise it will be readily understood that the process may be carried on as a continuous process by the provision of suit- 110

able means for continually introducing and withdrawing the liquid from the container 2 during the operation of forcing or introducing gases into said container and for continually supplying the gas; but as these also are well understood in the art they are not here shown. Gases not taken up by the liquid may be carried away from the chamber 2, through pipe 5, and used for any other purpose.

As will be readily understood, a series of containers for the coal and for bringing the liquid and the gases into contact therewith may be provided and used in succession to facilitate the manufacture in a practical way.

In the foregoing description and in the claims the term "petroleum" is to be understood as including mineral oil or products and distillates thereof other than the gasoline of commerce and that are deficient in the qualities of gasoline rendering the same particularly suitable for use as the fuel for internal combustion engines.

What I claim as my invention is:—

1. The improvement in the manufacture of hydrocarbon liquids consisting in heating a carbonized product of the vegetable kingdom sufficiently only to expel the lighter gases therefrom and constituting the smoke producing elements and exposing petroleum

to the lighter gases to produce a hydrocarbon liquid suitable for use in internal combustion engines.

2. The improvement in the manufacture of hydrocarbon liquids consisting in heating a carbonized product of the vegetable kingdom sufficiently only to expel the lighter gases therefrom and constituting the smoke producing elements and bringing the said lighter gases into contact with petroleum of a comparatively low temperature to produce a hydrocarbon liquid suitable for use in internal combustion engines.

3. The improvement in the manufacture of hydrocarbon liquids consisting in heating coal sufficiently only to expel the lighter gases therefrom and constituting the smoke producing elements and bringing said lighter gases into contact with petroleum to produce a hydrocarbon liquid suitable for use in internal combustion engines while leaving the coal with substantially all its heat producing units but free from the smoke producing elements.

Signed at New York, in the county of New York and State of New York, this 5th day of March, A. D. 1917.

CHARLES F. WINCH.
